FIG. 4.

UNITED STATES PATENT OFFICE.

JAMES MACDONALD, OF NEW YORK, N. Y.

HYDROSTATIC LEVELING-INSTRUMENT.

SPECIFICATION forming part of Letters Patent No. 327,564, dated October 6, 1885.

Application filed June 11, 1885. Serial No. 168,305. (No model.)

To all whom it may concern:

Be it known that I, JAMES MACDONALD, of the city, county, and State of New York, have invented certain new and useful Improvements 5 in Hydrostatic Leveling-Instruments, of which the following is a description, reference being had to the accompanying drawings, in which—

Figure 1 is a view of said instrument, one of the standards being shown in section and 10 the other in elevation, the connecting-tube of which is broken. Fig. 2 is an enlarged vertical sectional view in detail of a portion of the top of one of the tubes, showing the construction 15 of the valve therein. Fig. 3 is a bottom view of the screw cap and valve, taken on the line $x-x$, Fig. 2, viewed in the direction of the arrow there shown. Fig. 4 is a plan view of the ring-nut by which the inner tube is fastened within the case, and Fig. 5 is a plan view 20 in detail of one of the ring clasps or indicators attached to the standards respectively.

Like letters of reference indicate like parts in the different figures.

My invention relates to certain improvements 25 in hydrostatic leveling-instruments for the purpose of ascertaining the levels of different planes of varying altitude, where it is impracticable, by reason of intervening obstructions or otherwise, to utilize the ordinary 30 level; and my object is, first, to provide a simple and effective means to ascertain and gage the height of the liquid in the respective tubes with the utmost accuracy, in connection with a suitable scale; second, to provide a 35 simple and effective means whereby, when said level has once been attained, the liquid in said tubes may be temporarily preserved in a fixed position while the instrument is removed for examination; and, third, to provide a valve 40 mechanism whereby the vent which supplies air to said tubes respectively may be automatically closed, so as to prevent a loss of liquid upon an accidental overturning of the tubes.

45 In the drawings, A A represent two standards, which consist of hollow shells or cylinders, preferably of brass, each of which is provided with a suitable base, A', into which the same is inserted and attached by means of 50 cement, a screw-thread, or otherwise.

Within the shells A are inserted glass tubes

B B, against the respective ends of which are placed rubber rings or washers b b, Figs. 1 and 2, when the whole is secured firmly in place by means of a screw-ring, b', provided 55 with slots b' b', Fig. 4, whereby the same may be screwed within the screw-threaded interior of the top of the shell A, sufficient space being left above the same for the reception of a screw-threaded cap, C. Said cap is provided with 60 the usual milled flange, c, a central opening or perforation, c', and a bottom plate, c'', better shown in Figs. 2 and 3, which is preferably swaged into position, as shown, leaving a 65 space or chamber, c'', between said plate and the top, into which is loosely inserted an inverted conoidal-shaped cup or valve, D, the lower end of which is caused to protrude through the plate c'' in order to retain the same in an upright position, while said protruding 70 portion is made smaller than that above, leaving a shoulder, d, thereon to retain said cup within the cavity c''. The perforation in the plate c'' through which said cup protrudes is made preferably of a triangular or other 75 irregular shape, as shown in Fig. 3, so that, while the cup D is prevented from moving laterally, one or more air-passages is provided at the side thereof, so that when the cup is in its normal position, as shown in Fig. 3, the 80 air is free to pass downwardly through the vent c', around the cup and into the tube B. The interior of the base A' is bored downwardly, as at a, Fig. 1, so as to communicate with a lateral opening or passage, a'.

Tubes or necks A' A' are screwed into the base A' to communicate with the apertures a', said tubes being provided with the usual corrugations or enlargements for the reception and retention of a flexible rubber tube, E, 90 stretched thereover, by which said standards are connected. Each of said necks A' is provided with a stop-cock or cut-off, a'', for the purposes hereinafter named.

Upon opposite sides of each of the shells A, 95 I place slots a' a'', one of which is shown in the left hand in Fig. 1, and the other indicated in dotted lines upon the right. Upon one side of one of said slots in each of said standards I place a suitably-numbered gage 100 or scale, a', in connection with which I provide a ring-clasp or indicator, F, upon which

is shown, by preference, a Vernier scale, *f*. The standards *A A* are shown upon different levels *G G'*. The stop-cocks *a² a²* being open the liquid within the tubes assumes the level shown by the dotted lines *y y*. The rings *F F* are moved to indicate this position, and the cocks *a² a²* turned to retain said liquid in place, after which the standards may be removed elsewhere, if desired, and the scales 10 carefully examined. Should said tubes be overturned or the respective altitudes of the standards changed too much to correspond with the height of the tubes, the liquid therein is forced into one or both of the cups *D* and the vent *c'* closed, thus preventing leakage.

15 While I prefer to use two stop-cocks, it is obvious that one may accomplish a like purpose, the same being placed either upon one of the necks *A'*, as shown, or at any intermediate point between the two standards.

20 Having thus described my invention, I claim—

1. The combination, in a hydrostatic leveling-instrument, of the standards *A A*, united 25 by means of a flexible tube, ring-clasps or indicators *F F*, one or more stop-cocks, *a² a²*, and conoidal cup-shaped valves *D D*, with the per-

forated tops *C*, substantially as and for the purposes specified.

2. In a hydrostatic leveling-instrument, the 30 conoidal cup-shaped valves *D D*, provided with supports for loosely sustaining the same in suitable positions respectively near perforations or vents in the tops of the standards, whereby a pressure of liquid within one or the 35 other of said valves may automatically close the vent, substantially as described.

3. The combination, with the standards, of a hydrostatic leveling-instrument, of the perforated cap *C*, valves *D D*, and a perforated 40 plate *c'*, for sustaining said cup-valves loosely in an upright position, substantially as specified.

4. The combination of the perforated caps *C C*, cups *D D*, and plates *c' c'*, each of the latter being provided with one or more air-passages at the side of and adjacent to said cups, substantially as and for the purposes specified. 45

JAS. MACDONALD.
